UNITED STATES PATENT OFFICE.

HERBERT W. BEATTIE, OF QUINCY, MASSACHUSETTS, ASSIGNOR TO SILL STOVE WORKS, OF ROCHESTER, NEW YORK, A CORPORATION OF NEW YORK.

DESIGN FOR A STOVE.

SPECIFICATION forming part of Design No. 37,251, dated November 29, 1904.

Application filed October 31, 1904. Serial No. 230,859. Term of patent 14 years.

To all whom it may concern:

Be it known that I, HERBERT W. BEATTIE, a citizen of the United States, residing at Quincy, in the county of Norfolk and State of Massachusetts, have invented a new, original, and ornamental Design for Stoves, of which the accompanying drawing is a representation.

The figure is a perspective view of a stove, showing my new design.

What I claim as new, and desire to secure to by Letters Patent, is—

The ornamental design for a stove as herein shown.

HERBERT W. BEATTIE.
